UNITED STATES PATENT OFFICE.

DANIEL E. HENNESSY, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

FABRIC AND METHOD OF TREATING SAME.

Application filed January 12, 1925. Serial No. 1,864.

My invention relates to the art of manufacturing pneumatic tire casings and more particularly to a method of preparing fabric to be used in building the carcass of such 5 casings. The fabric used for this purpose is either square woven, or so called cord or weftless cord fabric, herein generically termed fabric, which has been calendered or otherwise rubberized. The fabric after calendering 10 is rolled in a liner of duck or other suitable material. From this rubberized web, strips of desired width are cut, the cut being usually on the bias, in other words so that the strain resisting elements lay at an angle to the length of the cut strip. According to 15 prior practice the strips of fabric as they are severed are laid by hand into a liner which is rolled up and from which they are later removed as required to be formed into bands 20 or spliced into lengths as the type of building machine may require.

The old method of severing and handling the fabric strips or plies require a relatively large number of operators to remove the 25 fabric from the bias cutter, lay it smoothly in the liner and wind it into rolls. The rubberized fabric is sticky and difficult to handle and at the speed at which the cutting machine is necessarily run wrinkles and folds occur in 30 the cut plies even when care is used by the operators which cause delay and waste when the fabric is later removed from the liners.

It is among the objects of my invention to provide a method of cutting the fabric which 35 will decrease the number of operators at the cutting machine and permit the fabric to be mechanically wound into the liners, to prevent the occurrences of folds and wrinkles and to decrease the amount of liner material 40 required. Other and further objects will appear from the following specification and claim.

In the accompanying drawings which illustrate one embodiment of my invention—

45 Figure 1 is a diagrammatic side elevation of means for carrying out my method.

Figure 2 shows a portion of a fabric web treated according to my invention, and

50 Figure 3 is a fragmentary section of treated fabric on a greatly enlarged scale.

Referring to Figure 1, 1 designates generally a roll of rubberized fabric 4 wound in a suitable liner 5. A conventional bias cutting machine is indicated at 2 and means for winding up the treated fabric in the liner is shown

5 at 3. In carrying out my method I set the knives of the cutter so that while the fabric itself is substantially severed the rubber coating on one side remains intact and retains the strips in connected relation as indicated at 6 60 in Figures 2 and 3. In the latter figure the fabric is shown at 4, the coatings of rubber being indicated at 8.

Referring again to Figure 1 the fabric as it leaves the roll 1 is drawn forward and thru 65 the cutting machine. The liner 5 passes beneath the cutter to the windup mechanism 3 where it again meets the now partially severed fabric. The fabric unrolling, cutting and windup mechanism may be of any suitable 70 type and specific description thereof is believed unnecessary.

It will be understood that if desired the treated fabric may be wound into a separate liner of any desired length instead of into the 75 liner from which the untreated web is taken.

The cut strips being unseparated as they are wound into the wide liner there is no chance of wrinkles and folds occurring at the edges and ends as is the case when the strips are 80 separated and separately placed in the liners. When the strips are to be used the treated roll of fabric is placed in a suitable supply rack and unwound, the strips being easily separated from the web as indicated at 7 in Figure 85 2.

Having described one embodiment of my invention I claim:

The method of cutting and handling a relatively wide web of tire material, formed of 90 tire fabric bonded between two layers of rubber, which comprises forming successive cuts crosswise of the web and through the upper layer of rubber and the fabric without disrupting the underlying layer of rubber, the 95 line of said cuts being on the bias with respect to the length of the web, and winding the so cut web into a liner directly, and continuously from the cutting machine, one end of the so cut diagonally positioned sections entering 100 the liner roll first, without tendency to disrupt the uncut layer of rubber and without presenting transverse severed edges, to form a uniform compact roll in which the tire material is substantially coextensive with its protecting liner.

In testimony whereof I have signed my name to the above specification.

DANIEL E. HENNESSY.
